DESIGN FOR A SAND TOY

Oscar Fisher, Locust Valley, N. Y.

Application August 17, 1944, Serial No. 114,919

Term of patent 14 years

(Cl. D34—15)

To all whom it may concern:

Be it known that I, Oscar Fisher, a citizen of the United States, residing in Locust Valley, county of Nassau and State of New York, have invented a new, original, and ornamental Design for a Sand Toy, of which the following is a specification, reference being had to the accompanying drawing, forming a part thereof, in which:

Fig. 1 is a perspective view of the sand toy showing my new design; and
Fig. 2 is a side elevation thereof.

I claim:

The ornamental design for a sand toy, as shown.

OSCAR FISHER.
